Primary Examiner — Justin C Dodson*Assistant Examiner* — Sydney M Evans(74) *Attorney, Agent, or Firm* — Stevens Patent Law LLC; James Stevens(57) **CLAIM**

The ornamental design for water pump pliers, as shown and described.

DESCRIPTION

FIG. 1 is a perspective view of water pump pliers showing our new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.
